UNITED STATES PATENT OFFICE.

GUSTAF M. ANDERSSON, OF NEWARK, NEW JERSEY, ASSIGNOR TO HENNING
G. TAUBE, OF SAME PLACE.

CENTRIFUGAL APPARATUS.

SPECIFICATION forming part of Letters Patent No. 555,893, dated March 3, 1896.

Application filed September 19, 1892. Serial No. 446,243. (No model.)

To all whom it may concern:

Be it known that I, GUSTAF M. ANDERSSON, a subject of the King of Sweden and Norway, and a resident of Newark, in the county of 5 Essex, State of New Jersey, have invented certain new and useful Improvements in Centrifugal Separating Apparatus, of which the following is a specification, reference being had to the accompanying drawings, forming 10 part hereof.

This invention relates generally to centrifugal apparatus for separating substances of different specific gravities, but it is more especially designed for centrifugal cream-separators and centrifugal butter-extractors.

It has for its object to secure a delicate adjustment of a fluid-outlet from the drum or from a chamber of the separating-drum.

In the accompanying drawings, Figure 1 is 20 a plan view of a centrifugal butter-extractor. Fig. 2 is a vertical section of the same on the line 2 2, Fig. 1. Fig. 3 is a vertical section on the same line, but looking in opposite direction. Fig. 4 is a horizontal section on the line 4 4, Figs. 2 and 3. Fig. 5 is a detail perspective of the adjustable outlet. Fig. 6 is a detached perspective of the cream-disturber. Fig. 7 is a vertical central section of a centrifugal separator, showing my improvements applied thereto.

The apparatus shown in the drawings is especially adapted for hand-operated butter-extractors and cream-separators, and to that end the various parts are of simple compact 35 construction and are especially light running, so that there is but slight friction and therefore little waste of power in the operation of the machine.

The drawings do not show the lower parts 40 of the apparatus nor the bearings for the centrifugal drum, as these parts are of ordinary construction and well understood in the art.

The centrifugal drum or bowl is incased by a fixed casing *b*, provided with a removable 45 cover *b'*. The operating-shaft *c* is arranged vertically and rotatively mounted in bearings of usual construction, and the separating drum or bowl *a* is mounted upon the upper end of this operating-shaft *c*. In the operation of the machine this drum is revolved at

the rate of from six thousand to eight thousand revolutions per minute.

The mixed substances to be separated must be fed into the machine in a substantially fluid condition, and are preferably supplied 55 in a continuous but regulated stream from the vessel *e*, mounted upon the cover *b'* and provided with a downwardly-projecting pipe or feed-tube *f*. This feed-tube extends down into the receiving-chamber or spread-cup *g* of 60 the separating-drum, provided with radial outlets or tubes *g'*, which extend into the main separating-chamber of the drum.

f is the feed-tube through which milk is supplied to the bowl *a* from the reservoir *e*. 65

h is the color-cup for supplying coloring matter for the butter and is adjustably mounted in a screw-threaded bearing in the vessel *e* and has a downwardly-extending tube *h'* entering the feed-tube *f*. The lower 70 end of the tube *h'* is conical, as preferably is also the lower end of the feed-tube *f*, and the tube *h'* is therefore adapted to act as a stopper for the feed-tube *f*, and by its position in the feed-tube regulates the amount of opening 75 or the size of the passage for the fluid supplied to the separating-drum.

The adjustment of the adjustable sliding plug *h* determines the amount of coloring material fed into the extractor, and the adjustment of the color-cup as a whole determines the amount of milk fed into the extractor.

Within the main chamber of the drum radial blades *i* of ordinary construction are 85 provided to compel the fluid to partake of the rotation of the drum. The outlets from the main separating-chamber for the heavier material are tubes *j*, extending from the outer periphery of the separating-drum to a point 90 quite near the axis of the separating-drum, and there connected with the inclined cylindrical openings *j'*. The outlet for the lighter fluid is an adjustable plug *a*, rotatively mounted in an opening in the upper wall of 95 the main separating-chamber of the drum and preferably screw-threaded exteriorly. This outlet-plug is pierced eccentrically, so that when this outlet-plug is turned the orifice will be moved toward or from the axis of 100

the separating-drum. The orifice is preferably rectangular in cross-section, so that the plug may be turned by inserting a suitable key or wrench in said orifice a' .

5 The outlet-plug a is located at a distance from the axis of the drum corresponding very nearly with the radius of the inner wall of the fluid within the drum during the operation of the drum. The intense centrifugal 10 force resulting from the rapid revolution of the drum causes the separation of the particles of the fluid and a rearrangement of the particles according to their specific gravity, the heavier particles arranging themselves 15 near the periphery of the drum and the lighter particles arranging themselves nearest the axis of the drum. Now the position of the outlet a' for the lighter particles determines the density of the lighter fluid that passes 20 out through such outlet a' , for the reason that the outlet for the heavier fluids is fixed, and the relative positions of these two outlets determine through the equilibrium of the fluids the density of the fluid which will flow out 25 through the outlet a' . As the fluid supplied to the separating-drum is not always of the same consistency, it becomes necessary at various times to slightly adjust the outlet a' , even when the device is always used upon the same 30 character of material, as well as to initially delicately adjust the outlet. This is well illustrated in cream-separating and butter extraction, where the milk supplied to the machine is of varying densities and is especially 35 changed by the change of locality, so that each machine has to be adjusted to the character of cream supplied at the locality in which it is used. It is therefore quite desirable to have a fine adjustment, such as is 40 provided by my eccentrically-pierced plug a , in order to adapt the machine to the production of a uniform quality of butter or cream.

In the construction shown in Fig. 7, where my invention is applied to a centrifugal 45 cream-separating device, the drum has but one separating-chamber, and the cream-outlet plug a is arranged at the upper part of the drum, and the cream escapes from this outlet and is thrown outward into a receiving-pan k . 50 This construction is also adapted for the separation of other substances than cream and milk, and is in fact a centrifugal separating apparatus of general utility. When, however, my invention is to be applied to butter extraction, additional devices are necessary 55 to separate out the last particles of blue milk, and thus effectually separate the butter-fat from the blue milk, and one or more additional chambers are provided in which this operation is effected. This construction is shown 60 in Figs. 1 to 6, inclusive. These devices for extracting butter form no part of my present invention. Any suitable apparatus for extracting butter may be used in their place. They 65 are, however, shown in the drawings, and will be now described so as to clearly show one manner of using my improved eccentrically-

pierced screw-plug with butter-extracting devices. Two chambers are provided in the upper part of the separating-drum. The lower 70 chamber, l , receives the cream from the cream-outlet a' . Within this chamber is arranged the cream-disturber, consisting of the stationary comb or pins m , mounted upon the stud m' and arranged to extend within the chamber so that their ends will enter the inner layer or wall of lighter material within the chamber l . The stud m' is rotatively adjustable and is mounted in the top or cover b' of the casing, and is adjusted by means of the handle m^3 adapted to be clamped in desired position, and is partly hollow, and has a tube or spout m^2 projecting into the upper chamber, n , of the separating-drum. This upper chamber, 80 n , is placed just above the chamber l and receives the butter from such chamber l . By means of the tube or spout m^2 water or other lubricating fluid is supplied to this upper chamber, n , and floats the butter particles inward in position to be removed from the machine by the butter-knife. This butter-knife 85 o is adjustably mounted in the top or cover b' of the casing and projects downward into the upper chamber, n , of the drum. The operation of this butter-knife is to cut out or scoop 90 out the butter from the inner layer within the chamber n .

A drip-pan p is mounted in the upper part of the casing to receive any fluid which may perchance flow over the top of the drum. A 100 suitable vessel would also be provided or formed by the casing for receiving the blue milk from the outlet-orifices j' , but such device is not shown, as it is of usual and well-known construction.

The apparatus shown in the drawings is convertible—that is to say, the same frame and separating-drum is adapted, with a slight change of other parts, to operate both as a butter-extractor and as a separator. The 110 change from one form of machine to the other is readily and easily effected.

Figs. 1 to 6 show the apparatus arranged for butter extraction, and Fig. 7 shows the apparatus arranged for simple separation. 115 The removal of the cover b' and attached parts, including the drip-pan p , the vessel e , tube f , and the separating-combs m and stud, and of the upper revolving piece containing the chambers n and l , and spread-cup g^3 and the outlet-orifice a' , removes all the parts of the machine that are peculiar to the butter-extracting operation. The removal of these parts having been effected, the cap q is screwed upon the separating-drum and the cover r is 120 placed over the top of the frame b , and thereby the machine is prepared for the operation of separating cream from milk or of separating other mixed substances. A suitable reservoir or vessel e' forms part of the cover r , 125 and a suitable receiving-vessel k also forms part thereof. A feed-tube f' extends downward from the bottom of the vessel e' into a receiving-chamber or spread-cup formed in 130

the cap q . This spread-cup is similar in construction to the spread-cup g^2 of the butter-extracting cap, but somewhat modified by reason of the different shape of cap. g^3 are 5 the tubes extending from such cup into the main chamber of the drum.

An adjustable plug a , provided with an outlet-orifice a' , is exactly of the same construction as that heretofore described and 10 mounted within the top of the cap.

The feed-tube, color-cup, and its downwardly-extending tube, the adjustable sliding plug, and the butter-extracting devices shown and described form no part of my present invention, but are to be claimed in another application about to be filed by me. 15

What I claim, and desire to secure by Letters Patent, is—

1. In a centrifugal separator, the combination with the separator-drum of an eccentrically-pierced rotatable plug fitted in the walls of a separating-chamber of said drum and so arranged that the rotation of said plug 20 adjusts the distance from the axis of the drum to said eccentric opening, substantially as set forth.

2. In a centrifugal separator, the combination with the separator-drum of the rotatable screw-plug a , having the eccentric orifice a' formed therein and fitted in the walls of a 25 separating-chamber of said drum, substantially as set forth.

GUSTAF M. ANDERSSON.
